(57) **CLAIM**

We claim the ornamental design for a bone implant, as shown and described.

DESCRIPTION

FIG. 1 is a front perspective view from below of the claimed design;

FIG. 2 is a bottom view from above of the claimed design of FIG. 1;

FIG. 3 is a left side view of the claimed design of FIG. 1, the right side view is identical to the left side view;

FIG. 4 is a front view of the claimed design of FIG. 1, the rear view is identical to the front view;

FIG. 5 is a front perspective view from above of the claimed design of FIG. 1; and,

FIG. 6 is a top view of the claimed design of FIG. 1.

Any portion of the article depicted in broken lines forms no part of the claimed design.
